UNITED STATES PATENT OFFICE.

MARY SZYMOINSKA, OF CARLOS, TEXAS.

CUSPIDOR.

1,082,371.

Specification of Letters Patent. Patented Dec. 23, 1913.

Application filed May 6, 1913. Serial No. 765,831.

To all whom it may concern:

Be it known that I, MARY SZYMOINSKA, a citizen of the United States, residing at Carlos, in the county of Grimes and State 5 of Texas, have invented new and useful Improvements in Cuspidors, of which the following is a specification.

This invention relates to a cuspidor and has for its primary object to provide a device of this character which is adapted especially for use upon railway cars, boats, or the like.

A further object of the invention is to provide a cuspidor which comprises a hollow body adapted to be mounted within the floor of a car, and means disposed in a partially concealed and unobstructing position for maintaining the lower end of the body closed during use, means being provided for locking the closing device, which is adapted normally to assume open position, in closed position, so that a train porter or other operator may conveniently effect the release of the closing means for the cuspidor when it 25 is desired to discharge the contents therefrom and clean the same, and so that he may readily move the closing device into operative position and may lock the same therein.

A still further object is the provision of a 30 cuspidor of the class set forth which is of the simplest possible construction whereby the device is rendered inexpensive in the cost of manufacture, capable of being readily and cheaply installed, and, efficient and 35 easy to operate when in use.

The invention consists in the features of construction, combination and arrangement of parts hereinafter fully described and claimed, reference being had to the accompanying drawing, in which:

Figure 1 is a top plan view of the device mounted in the floor of a car; Fig. 2 is a vertical sectional view taken therethrough, showing the closing device locked in operative position, the position of the locking member when inoperative being shown in dotted lines; and Fig. 3 is a similar sectional view showing the closing device in its inoperative position.

In the drawing, the numeral 1 designates the body of the cuspidor which is shown supported by the floor 2 of a car, or the like, with its reduced, cylindrical portion 3 depending through an opening 4 in the floor. The upper end of the body is provided with a flared mouth 5 in communication with the

longitudinal bore 6 thereof which extends through the lower end of the reduced portion 3. A closure plate 7 for the lower end of the body is hinged thereto as at 8 for vertical swinging movement and is adapted to engage the lower end of the reduced portion 3 evenly when in its operative position. An arm 9 extends laterally from the closure 7 on the opposite side of its point of pivotal connection to the body and is connected with the supporting floor by means of a helical extensile spring 10 which is adapted to hold the arm 9 normally in its uppermost position with the closure in its open, inoperative position. It is to be understood, however, that the spring 10 may connect the said arm with the reduced portion 3 of the body of the device if desired.

An operating rod 11 has its lower end 75 pivotally connected with the outer end of the closure arm 9 as at 12 and extends upwardly therefrom through a vertical opening 13 provided in the floor 2. This rod is provided with a shoulder 14 adapted to engage beneath the floor at the outer edge of the opening 13 when the closure 7 is in its operative position and the said rod is swung outwardly. A locking member 15 is pivotally connected to the protruding upper end 85 of the rod 11 for vertical swinging movement and is adapted to have the extremity of its short arm 16 engaged with the upwardly and outwardly inclined inner face 17 of a notch provided in the adjacent edge of the 90 body 1, so that upward movement of this arm as caused by depression of the opposite manipulating arm 18, will cause the upper end of the rod 11 to be forced outwardly into its locked position just described. A 95 locking member 15 is adapted to secure the rod 11 in this position when it is desired to maintain the lower end of the cuspidor closed during its active use. The outer end of the arm 18 of the said locking member is provided with a notch 19 affording a finger-hold whereby the same may be readily grasped when it is desired to turn the same into its releasing position, during which movement the extremity of its arm 16 will 100 engage the upper end of the rod 11, so that inward pressure of the member 15 will remove the upper end of the rod 11 from engagement with the floor and thus permit the same to move upwardly as caused by the 105 action of the spring 10.

When it is desired to close the lower end

of the cupidor, the locking member 15 is pushed downward and is then swung outwardly and downwardly so as to bring the extremity of its arm 16 into engagement with the beveled face 17 and thus effect the locking of the closure in its operative position, in the manner which has been previously described.

From the foregoing description, taken in connection with the accompanying drawing, it should be apparent that I have provided a simply constructed and efficient cupidor which may be used conveniently upon railroad cars, boats, or public vehicles of different kinds and which may be opened for the purpose of cleaning the same with a minimum expenditure of time and energy.

Having thus described my invention what I claim is:

20 The combination with a support, of a cupidor attached thereto and comprising a depending, hollow body having its lower end open, a closure for the said end of the body pivotally connected thereto for vertical swinging movement, an arm projecting laterally from the closure oppositely with respect to its point of pivotal connection to the body, the said support being provided with a vertical opening adjacent to the body,

an operating rod connected to the extremity 30 of the said arm and extending upwardly through the said support opening for vertical reciprocation and slight oscillatory movement therein, yieldable means for normally maintaining the said closure in its inoperative position with the operating rod in its uppermost position, means provided upon the said rod for engagement with the under face of the support when in its lowermost position to maintain the closure locked when the upper end of the operating rod is swung laterally, the body of the device being provided in its exterior portion with a recess having an inclined inner face, and a locking lever pivotally connected to the free end 40 of the operating rod with one of its arms constructed shorter than the width of the support opening and adapted for terminal engagement with the said inclined face of the body recess, the opposite arm of the lever 45 being engageable with the upper face of the support.

In testimony whereof I affix my signature in presence of two witnesses.

MARY SZYMOINSKA.
